PHILIP MALCAMP, OF NEW ORLEANS, LOUISIANA.

LAMP.

1,158,419.

Specification of Letters Patent. Patented Oct. 26, 1915.

Application filed December 12, 1914. Serial No. 876,829.

To all whom it may concern:

Be it known that I, PHILIP MALCAMP, a citizen of the Republic of France, and a resident of New Orleans, in the parish of Orleans and State of Louisiana, have invented 5 a new and useful Improvement in Lamps, of which the following is a specification.

My invention is an improvement in lamps, and has for its object to provide a lamp of 10 the character specified, adapted for burning liquid fuel, as for instance, kerosene, and so arranged that it may be used for lighting, heating and cooking, and wherein means is provided for regulating the combustion of 15 the fuel to produce the results desired.

In the drawings: Figure 1 is a vertical section of the improved lamp, Fig. 2 is a top plan view of the burner portion of the lamp, and Figs. 3 and 4 are sections on the lines 20 3—3 and 4—4, respectively, of Fig. 2.

The present embodiment of the invention comprises a base consisting of a tank or reservoir 1, for containing fuel, and having a central draft tube 2, the wick 3 being of 25 cylindrical form and encircling the tube. The tank has a nipple 4, which encircles the draft tube and is held coaxial therewith, and the tank or reservoir is supported by legs 5.

A plate 6 is arranged diametrically of the 30 draft tube at the bottom thereof, the plate having a central opening and a frusto-conical guide 7 is seated on the plate at the center thereof, the small lower end of the guide registering with the central opening 35 of the plate. The guide has a marginal flange 8 at its small end, and this flange seats on the upper face of the plate.

A rod 9 is mounted to slide vertically 40 through the opening of the plate and the lower end of the rod rests upon the inner end of a lever 10, whose outer end is provided with a weight 11. The lever is pivotally mounted, having a transverse pin 12, near its outer end, and the pin is received in 45 notches in arms 13, extending outwardly from a bracket plate 14. The bracket plate is curved transversely and the upper end thereof is secured to a ring 15, which encircles the tank or reservoir, and is connected 50 thereto in any suitable or desired manner.

An angle plate 15' has one of its portions 55 secured to the outer face of the bracket 14, and the other portion of the angle plate extends laterally outward from the bracket and has an opening through which is threaded a set screw 17, the lower end of the set

screw engaging the lever 10 on the outer side of its pivotal connection. The angle plate provides a stop or an abutment through which the set screw is threaded to cause the screw to move longitudinally when it is rotated with respect to the abutment. The upper end of the rod 9 is threaded, and passes through an opening in the upwardly off-set central portion 18^a of a hood or 60 damper 18, and nuts 19 are threaded on to the rod above and below the hood to hold it in adjusted position. The hood is a circular plate or disk of conical form, and is provided with a radial notch or recess 20. 70

A ring 21 is arranged below the hood, the ring being supported by screw bolts 22, which pass downwardly through the hood and through the ring and are engaged by nuts 23, below the ring, and the ring is provided with an upwardly extending marginal flange 24 at its inner edge. This flange has an annular groove on its inner face at its top, and a cylindrical damper 25 is held by the ring. The damper is provided with 75 an annular groove at its upper end forming an external rib which engages within the groove of the flange of the ring, thus supporting the damper, and at its lower end the damper is provided with a marginal outwardly extending flange 26. The damper and the ring are both coaxial with the rod, and the lower end of the damper fits within a sleeve 27, having its upper end curved inwardly as indicated at 28. 80

There is a space between the adjacent edges of the flanges 26 and 28, and when these flanges are in the same plane this annular opening or space is at its smallest extent. When the damper 25 is lowered the 85 space is increased, as will be evident from an inspection of Fig. 1. The opening or recess 20 in the hood 18 may be closed by means of a plate 29, the said plate being held in position to cover the opening 20, by 90 means of one of the screw bolts 22. 95

It will be noted from an inspection of Figs. 1, 2 and 4 that the edges of the plate are offset upwardly at the opening 20, so that the body of the plate will fit within the opening. By means of the nut 23 of the bolt which holds the plate, the plate may be firmly secured in the opening. To move the plate it will be necessary to loosen the nut 23 in order that the plate may swing out of 105 the opening. 110

The wick is raised or lowered in the usual

manner, by mechanism connected with the shaft 30, the inner end of the shaft extending through an opening in the tank or reservoir, and being supported in a tube or sleeve 31, outside of the tank. The shaft is provided with a wheel 32 at its outer end for convenience in turning the same, and the sleeve is provided with an arm 33, adjacent to the wheel. The arm has a bearing 34 fitting around the sleeve and clamped thereon by means of a screw 35. The free end of the arm extends beyond the periphery of the wheel, and the outer corner of the arm adjacent to the tank or reservoir is beveled as shown more particularly in Fig. 3. An arm 36 is secured diametrically of the wheel, and at one end the arm extends beyond the wheel and is pointed. The arrangement of the arms 33 and 36 is such with respect to the wick and its operating mechanism, that when the upper end of the wick is flush with the upper end of the draft tube and the nipple 4, the point of the arm 36 will be in register with the point of the arm 33.

25 A screen 37 is arranged transversely of the sleeve 27 at its lower end, and a sleeve 38 is connected with the screen. The screen 37 is a plate, having circular openings, and a second screen 39 of perforate material is arranged below the screen 37. A plate 40 is arranged transversely of the lower end of the damper 25, the said plate having an opening through which the rod 9 passes. The rod also passes through a central opening in the screen 37 and through a guide 41 in the sleeve 38. The guide is connected to the screen 39 as shown in Fig. 1, and the sleeve 38 has longitudinally extending recesses 42, through which the connections between the guide 41 and screen 39 pass.

45 A chimney 45 of sheet metal, is arranged about the wick supporting mechanism, the said chimney being cylindrical in form and having openings 46 and 47 oppositely arranged. The opening 46 is closed by a window casing 48, having isinglass, and the opening 47 is closed by means of a door 49, the door also having openings covered by isinglass or the like, and permitting access to the interior of the chimney. At its lower end the chimney rests upon supports 50, to be later described, connected with the tank or reservoir.

55 Standards 51 extend upwardly from the tank or reservoir, and the said standards support a ring 52 at their tops. The standards are offset outwardly intermediate their ends for a purpose to be described, and a stove plate or griddle 53 rests within the ring. A tank or reservoir 54 of annular form is arranged above the chimney and below the ring 52, and the said tank has an annular cover 55 provided with a handle 56, extending radially therefrom. The tank or reservoir 54 is also provided with a dis-

charge valve 57 and with a handle 58 for convenience in placing or removing the same. The sleeve 59 that forms the interior of the tank is flanged outwardly at its lower end as indicated at 60, and this flange rests upon the outwardly flanged upper end 61 of the chimney. This sleeve 59 is open at its upper end, and an annular or ring-shaped cover 62 is provided for the said end. The cover has a depending flange 63, which fits within the sleeve, and the outer edge of the cover proper rests upon the inner edge of the cover 55 for the tank or reservoir 54. Each of the supports 50 as shown in Fig. 2, is formed from a strip of suitable material, 75 having a notch in one side edge and at the center of the strip. The strip is then doubled upon itself, and the ends are bent outwardly away from each other. The bent out ends are secured to the top of the tank 80 or reservoir 1, by rivets or the like, and the double portion forms a support for the chimney.

85 In operation, the tank or reservoir 1 is first filled preferably with a good grade of 90 kerosene, and the said tank or reservoir is provided with a filling opening normally closed by a cap 64. The wick is properly trimmed and dressed until it is perfectly 95 smooth and even with the upper edge of the nipple 4. The arms or indicators 33 and 36 should be in alinement, when the upper end of the wick is in the position noted, and after these things have been attended to the chimney or tube 45 is placed on the 100 supports 50. The tank or reservoir 54 is now placed and centered on the upper end of the tube 45. The standards 51 form a 105 guide for the proper placing of this tank. The said tank is designed to receive water, and it should be filled before the wick is 110 lighted. The cover 55 is placed on the tank, and with the left hand the operator presses downwardly on the weight 11, thus swinging the lever 10 as indicated in full lines in 115 Fig. 1. With the right hand the operator turns the set screw 17 until the lever is fixed in the full line position of Fig. 1. The pressing down of the outer end of the lever raises the inner end, thus lifting the rod and 120 parts connected therewith. The door 49 is now opened and the wick is raised slightly until the arm 36 is about one-half inch in advance of the arm 33. The wick is now 125 lighted and the door is closed. The wick is permitted to burn for a while to heat the damper, or at least until it is burning with a white flame throughout its area. When this state of affairs obtains, the set screw 17 is turned in the opposite direction, that is, 130 in a direction to release the outer end of the lever 10, and permit the inner end of the lever to be moved downwardly by its own weight and that of connected parts. As soon as the inner end of the lever begins to

descend the white flame begins to change to blue, and with every turn of the set screw the blue increases. This operation is continued until the proper color of flame is secured. It will occasionally happen that in changing the size of the flame a buzzing or vibrating noise will result. In order to stop this noise the set screw 17 is turned in a direction to lower the damper 18. Whenever it is desired to increase the height of the flame the set screw 17 is turned in a direction to swing the outer end of the lever downward and to raise the damper 18. When it is desired to decrease the size of the flame the set screw 15 is turned in the opposite direction. In order to extinguish the flame, the wheel 32 is turned until the arms 33 and 36 are in register and the damper 18 is lowered until it rests upon the upper end of the wick, extinguishing the flame.

The improved stove may be used for boiling water or the like, or for cooking articles, the water being boiled in the annular tank 54, while the articles are cooked on the griddle 53. It may be also used as a heater or as a source of light. For heating, the blue flame is used, while for light the white flame is necessary.

It will be noted from an inspection of Fig. 30 4, that the ring 21 is provided at its periphery on its under face with an annular groove 21^a, the said groove being directly above the wick of the lamp. This is an essential feature, for when the damper is lowered far 35 enough that portion of the ring at the groove will immediately extinguish the flame. As is known, when a wick is smooth and even and uniform it will produce a uniform flame. It is also known that when a wick is disturbed by attempts to raise or lower the same, it will become uneven and an irregular flame will necessarily result. The lamp may be used as a night lamp by moving the cover plate 29, that is, by opening the said 40 plate and covering the remainder of the wick with the ring 21. When the plate 29 is moved to uncover the opening with the ring resting just above the wick only that portion of the wick at the opening 20 will 45 be ignited, thus the lamp can be arranged to provide for a pilot burner, lighted and ready to ignite the remainder of the wick as soon as the ring is lifted. With one burner the improved stove can be used to cook simultaneously two or more articles, merely by placing one pan above the other and the griddle at the top.

It will be evident that with the improved stove a white or reading light may be obtained, or a blue flame for cooking. In addition the lamp may be used as a night lamp and as many cooking vessels may be arranged above as there is room for without increasing the amount of fuel used.

65 The lower end of the chimney is as shown

provided with an inwardly extending flange 7', the said flange being curved radially as shown, and the flange is of perforate material.

I claim:

1. A lamp, comprising a tank or reservoir having a central draft tube and supporting legs, a wick encircling the draft tube, the reservoir having a wick tube at the top of the draft tube encircling the wick, means 75 for raising and lowering the wick, a rod arranged at the axis of the wick tube, a lever pivoted intermediate its ends to the reservoir and having its inner end in position to engage the lower end of the rod, a counterbalance weight on the outer end of the lever, means engaging the outer end of the lever for raising or lowering the same, said means comprising a set screw, an abutment on the reservoir through which the set screw is 80 threaded to engage the lever outside of its pivotal connection, a damper connected to the upper end of the rod, said damper being concavo-convex and arranged with its concave face downward, a fixed sleeve within the upper end of the draft tube, said sleeve having an inwardly extending flange at its upper end, a cylindrical damper supported by the rod and having an outwardly extending flange at its lower end, a screen 90 within the fixed sleeve, and guides for the rod.

2. A lamp, comprising a tank or reservoir having a central draft tube and supporting legs, a wick encircling the draft tube, the reservoir having a wick tube at the top of the draft tube encircling the wick, means 100 for raising and lowering the wick, a rod arranged at the axis of the wick tube, a lever pivoted intermediate its ends to the reservoir and having its inner end in position to engage the lower end of the rod, a counterbalance weight on the outer end of the lever, means engaging the outer end of the lever for raising or lowering the same, a 105 damper connected to the upper end of the rod, said damper being concavo-convex and arranged with its concave face downward.

3. A lamp, comprising a tank or reservoir having a central draft tube and supporting legs, a wick encircling the draft tube, the reservoir having a wick tube at the top of the draft tube encircling the wick, means for raising and lowering the wick, a rod arranged at the axis of the wick tube, a lever pivoted intermediate its ends to the reservoir and having its inner end in position to engage the lower end of the rod, a counterbalance weight on the outer end of the lever, means engaging the outer end of the lever for raising or lowering the same, and a 115 damper connected to the upper end of the rod.

4. A lamp, comprising a tank or reservoir having a central draft tube and supporting 120

legs, a wick encircling the draft tube, the reservoir having a wick tube at the top of the draft tube encircling the wick, means for raising and lowering the wick, a rod arranged at the axis of the wick tube, a lever pivoted intermediate its ends to the reservoir and having its inner end in position to engage the lower end of the rod, a damper connected to the upper end of the rod and 10 extending at its outer edge above the wick, means in connection with the rod and draft tube for controlling the draft through the draft tube and operated by the movement of the rod, and means engaging the outer end 15 of the lever for raising the inner end and for holding it in adjusted position.

5. A lamp, comprising a tank or reservoir having a central draft tube and supporting legs, a wick encircling the draft tube, the 20 reservoir having a wick tube at the top of the draft tube encircling the wick, means for raising and lowering the wick, a rod arranged at the axis of the wick tube, a dam-

per connected to the upper end of the rod and extending at its outer edge above the 25 wick, means in connection with the lower end of the rod for raising the rod and for holding it in adjusted position, said damper having a radial opening at its edge, and a plate for closing the opening and movable 30 into and out of position over the opening.

6. A lamp comprising a tank or reservoir having a central draft tube, a wick encircling the tube, means for raising and lowering the wick, a rod arranged within the 35 draft tube, a damper connected with the upper end of the rod, said damper extending at its outer edge beyond the wick, means for raising and lowering the rod, said damper having a radial notch in its edge, and a 40 removable cover for said notch.

PHILIP MALCAMP.
